2 SHEETS—SHEET 2.

UNITED STATES PATENT OFFICE.

RANDOLPH MYERS AND JOSEPH GRADY FAULKINBERRY, OF ARDMORE, TENNESSEE.

FAN FOR SEWING-MACHINES.

1,226,572.

Specification of Letters Patent.

Patented May 15, 1917.

Application filed May 3, 1916. Serial No. 95,147.

To all whom it may concern:

Be it known that we, RANDOLPH MYERS and JOSEPH GRADY FAULKINBERRY, citizens of the United States, residing at Ardmore, 5 in the county of Lincoln, State of Tennessee, have invented a new and useful Fan for Sewing-Machines; and we do hereby declare the following to be a full, clear, and exact description of the invention, such as will 10 enable others skilled in the art to which it appertains to make and use the same.

This invention relates to the art of fans and the like, and more especially to an improved fan adapted for use in connection 15 with sewing machines for keeping the operator or seamstress cool.

One of the objects of the invention is to provide a fan apparatus for a sewing machine comprising an improved mechanism 20 having connections with a pulley on the sewing machine to impart motion to the fan, in combination with means upon one of the shafts of the mechanism for holding the mechanism out of operation.

25 Another object of the invention is to provide a spherical cage inclosing the fan, thereby protecting the fingers of the operator against injury.

Another object of the invention is to provide 30 a semi-spherical shield and deflector adapted to be adjusted, to direct the air or the breeze generated by the fan in different directions, suitable to the operator or seamstress.

35 In practical fields the details of construction may necessitate alterations, falling within the scope of what is claimed.

The invention comprises further features and combinations of parts, as hereinafter 40 set forth, shown in the drawings, and claimed.

In the drawings,

Figure 1 is a view in side elevation of a portion of a sewing machine, and illustrating 45 the fan mechanism as supported on a table or the like adjacent to the machine and being connected thereto.

Fig. 2 is a sectional view on line 2—2 of Fig. 1.

50 Fig. 3 is a sectional view on line 3—3 of Fig. 2.

Fig. 4 is a detail view of a device for holding the fan mechanism in and out of gear.

55 Fig. 5 is a sectional view on line 5—5 of

Fig. 2, more clearly disclosing the deflector.

Referring more especially to the drawings, 1 designates a suitable casing having a top or closure 2 which is secured in place 60 by means of screws 3. The casing 1 is provided with a lateral extension casing 4. Mounted in suitable bearings 5 and 6 of the lateral extension casing and the casing 1 is a shaft 6 having a bevel gear 7 at one 65 end and a pinion 8 adjacent the other end. Also mounted on the shaft 6 is a suitable fly wheel 9. The shaft 6 extends through an additional bearing 10 of a standard 11, rising from the bottom of the casing 1. The 70 bearings 5 project from one side of the lateral extension casing 4, and secured upon the shaft 6 by means of suitable pins 12 are collars 13 which are arranged intermediate and in contact with the bearings 5, thereby 75 preventing axial movement of the shaft 6. Secured by means of suitable rivets 14 to an extension 15 of the lateral extension casing 4 is an upwardly projecting extension casing 16, and mounted in bearings 17 of 80 the extension casing 16 is a vertical shaft 18 having suitable collars 19 fixed thereto and intermediate and adjacent the bearings 17, thereby preventing vertical axial movement of the shaft 18. The lower end of the shaft 18 85 has a suitable bevel gear 20, meshing with the bevel gear 7, and upon the upper extremity of the shaft 18 a suitable fan 21 is secured by means of a pin 22, so as to rotate with the shaft. The upper end of the casing 16 is 90 closed, however, this closed end is provided with an opening 23 for the shaft 18. Fitting the upper closed end of the extension casing 16 is a sleeve cap 24, to which a downwardly extending flange 25 of a 95 spherical protecting cage 26 is soldered at 27. It is to be noted that the upper part of the sleeve cap is reduced, and encircling the reduced portion is an annular band 28, integral with which a semi-spherical deflector 100 29 is constructed and which corresponds to the shape of the spherical cage 26. This deflector is provided with a suitable handle 30, whereby the same may be adjusted to direct the air or breeze from the fan in 105 any suitable direction. When adjusting the deflector 29, the circular band 28 moves upon the reduced portion of the sleeve cap. Mounted in a suitable bearing 31 of the casing 1 and in a bearing 32 of the standard 110

11 is a shaft 33 which is provided with a gear 34 and a grooved pulley 35. A suitable belt 36 engages the pulley 35 and the pulley 37 of the shaft 38 of the sewing machine 39. It is to be observed that when the machine is operated in the usual manner, motion is imparted to the belt 36, which transmits power to the pulley 35 and shaft 33, which, in turn, imparts motion to the shaft 6 through the medium of the gear 34 and pinion 8, and by virtue of the intermeshing bevel pinions 7 and 20 motion is imparted to the fan shaft 18. A collar 39^a is secured upon the shaft 33 by means of pins 40, said collar being designed to contact with the side of the bearing 32 of the standard 11, to prevent axial movement of the shaft 33 in the direction of the fly wheel 9. A wheel 41 having an outer round peripheral edge 42 is mounted upon the shaft 33, which is slidable in its bearings in the direction of the arrow *a*. A tubular holder 43 is secured by rivets 44 to the bottom of the casing 1. This tubular holder has a slot 45 in its wall, there being a vertical pin 46 mounted in said holder. The upper end of the pin 46 is rounded off, as shown at 47, and between the lower end of the pin 46 and the bottom of the casing 1 a suitable spring 48 is arranged, to hold the pin 46 in a raised position, with the lug 49 in contact with the upper end of the slot 45. The pin 46 and the holder 43 are so arranged relative to the wheel 41 that the round upper end 47 of the pin is in the path of the outer round peripheral edge of said wheel, as shown in Fig. 2, thereby preventing axial movement of the shaft 33 in the direction of the arrow *a*. However, by exerting sufficient pull upon the pulley 35 in the direction of the arrow *a*, the round peripheral edge of the wheel 41 will cam against the round end 47 of the pin 46, thereby depressing the pin out of the path of the wheel, and after the wheel 41 has passed the upper end of the pin 46, the spring 48 will elevate the pin from the other side of the wheel 41, thereby holding the gear 34 out of mesh with the pinion 8, in which case the belt 36 will operate the pulley 35 idly. A collar 51 upon one end of

the shaft 33 contacts with one side of the bearing 32 of the standard 11 and limits the shaft 33 in its axial movement in the direction of the arrow *a*, with the pin 46 upon 55 the other side of the wheel 41.

The invention having been set forth, what is claimed as new and useful is:—

1. In combination with a fan driving mechanism, a vertical shaft having a fan 60 upon its upper end, a cage inclosing the fan, a semi-spherical deflector corresponding in shape with and fitting the cage and being adjustably mounted for deflecting the air or breeze in different directions. 65

2. In a device as set forth, the combination of a casing having a fan-operating mechanism therein and provided with a vertical extension casing, a shaft driven by said mechanism mounted in said extension 70 casing and having a fan upon its upper end, a sleeve cap fitted upon the upper end of the extension casing and provided with a spherical cage inclosing said fan, said sleeve cap having a reduced portion, and a spherical 75 deflector having a circular band fitting the reduced portion adjustably, whereby the deflector may be adjusted in different positions to adjust the air or breeze in different directions. 80

3. In a device as set forth, the combination of a fan-driving mechanism having a driven fan shaft, and a casing in which said fan shaft is mounted, of a sleeve cap fitted upon the upper end of said casing provided 85 with a reduced portion and an adjoining shoulder to prevent the cap from moving downwardly on the casing, a spherical cage carried by the cap, a circular band fitting the reduced portion of the cap and having 90 an integrally connected semi-spherical deflector, the circular band being adjustable whereby the deflector may direct the air or breeze in different directions. 95

In testimony whereof I have signed my name to this specification in the presence of two subscribing witnesses.
